Patented Feb. 24, 1925.

UNITED STATES PATENT OFFICE.

HOMER P. CHANDLER, OF MANSFIELD, OHIO, ASSIGNOR TO THE OHIO BRASS COMPANY, OF MANSFIELD, OHIO, A CORPORATION OF NEW JERSEY.

CONDUCTOR SUPPORT.

Application filed March 19, 1924. Serial No. 700,210.

To all whom it may concern:

Be it known that I, HOMER P. CHANDLER, a citizen of the United States of America, residing at Mansfield, in the county of Rich-
5 land and State of Ohio, have invented cer-
tain new and useful Improvements in Con-
ductor Supports, of which the following is
a specification.

My invention relates to conductor sup-
10 ports and more particularly to that class of
supports for securing a trolley conductor or
wire to an overhead hanger.

One of the objects of my invention is to pro-
15 duce a device which can be secured to an
overhead hanger and in which the jaws can
be moved either into or out of engagement
with the trolley wire to grip or release the
same as desired.

Another object of my invention is to pro-
20 duce a device in which the jaws may be
moved into alignment with the conductor
after the device has been secured to an over-
head hanger.

Another object of my invention is to pro-
25 duce a device in which the jaws are free to
rotate without limit after the device has
been installed upon a hanger.

Another object of my invention is to pro-
30 duce a device in which the jaws are movable
toward and away from the hanger before
and after the jaws engage with the trolley
wire in order to assist in the installation of
the device upon the hanger prior to the
35 jaws gripping the trolley wire and to per-
mit vertical movement of the trolley wire
relative to the hanger under action of the
upward pressure of the trolley wheel, all
as later herein described.

My invention resides in the new and novel
40 construction, combination and relation of
the various parts hereinafter more fully de-
scribed and disclosed in the drawing ac-
companying this specification.

In the drawing:

45 Fig. 1 shows a side view in elevation of
my invention as secured to a trolley wire.

Fig. 2 is an end view of Fig. 1.

Fig. 3 is a transverse view in section of
Fig. 1 taken on the line 3—3 and also shown
50 as secured in position on an overhead hang-
er.

Fig. 4 is a longitudinal section taken on
the line 4—4 of Fig. 2.

Fig. 5 is a sectional view corresponding to

Fig. 3, but with the jaws opened to receive 55
the trolley wire.

Fig. 6 is a transverse sectional view show-
ing the engagement of certain parts em-
ployed in securing a device to the overhead
hanger. 60

Fig. 7 is a sectional view on the line 7—7
of Fig. 3.

In the preferred construction embodying
my invention, I employ a supporting mem-
ber 1 internally threaded to receive the
threaded stud S of the overhead hanger H.
The member 1 is provided with an outwardly
extending flange 2 and the flange 2 is
provided with a stop lug 3. Mounted upon
the supporting member 1 is an operating
member 4 which is supported by the sup-
porting member 1 through the inwardly
projecting flange 5 engaging the flange 2.
The operating member 4 is provided with an
internally threaded portion 6. Threadably
engaging the portion 6 is an intermediate
member 7 provided with the threads 8 en-
gaging with the threads on the operating
member. The intermediate member is pro-
vided with a slot 9 adapted to engage with
the lug 3, but normally held out of engage-
ment with the lug 3 by the interposed spring
10. The member 1 is normally free to ro-
tate relative to the operating member 4 and
to the intermediate member 7, but when the
lug 3 engages with the slot 9 the parts 1 and
7 are interlocked and when either part is
rotated the other part must rotate sim-
ultaneously and in the same direction. There
is no interlocking, however, between the 90
member 1 and the member 4.

Projecting from the lower end of the
member 7 is a lug 11 provided with an open-
ing to receive the pin 12. Secured to the
lug 11 and in pivotal relation thereto by
means of the pin 12 are two jaw members 13
provided with lips 14 at their lower edge to
engage a trolley wire 15. The jaws are
mounted on the pin 12 by means of the in-
wardly projecting lugs 16 arranged in pairs
on each jaw and they alternate with the lugs
on the opposite jaw, as shown in Fig. 7. 95

The upper end of the jaws 13 are each
provided with an annular flange 17 of con-
siderable extent and a much shorter flange
18 forming a groove or channel 19 there-
between. Positioned within the groove or
channel 19 of each jaw is an annular flange
105

- 20 projecting from the lower portion of the operating member 4. The flange 20 engages the flange 17 to move the jaws 13 into engagement with the trolley wire and to hold them in such engagement. The flange 20 engages the flange 18 on each jaw to move the jaws out of engagement with the trolley wire or to open the jaws to receive the trolley wire and maintains the jaws in an open position. The operating member 4 is free to rotate relative to the jaws and is provided with a plurality of faces 21 to receive a wrench or other tool whereby the member 4 may be rotated.
- 15 It will be noted that if the operating member 4 is rotated relative to the jaws 13, that the operating member will move along the longitudinal axis of the device in a direction toward or away from the jaws, depending upon the direction of rotation, and that if the member 4 is so rotated as to move toward the jaws, that the jaws will be moved into a gripping engagement with the trolley wire 15, but if the member 4 is rotated so as to move away from the jaws 13 that the jaws will be moved further apart at their lower edge or out of gripping engagement with the trolley wire, and that regardless of how the jaws may be moved, they will be maintained in an opened or closed position through their interlock with the member 4.
- 20 It will also be observed that if the intermediate member 7 is brought into interlocking relation with the supporting member 1 through the lug 3 engaging with the slot 9, that the member 1 will be caused to rotate in unison with any rotation of the parts 13.
- 25 It will also be evident that when the device is installed on a hanger, as shown in Fig. 3, that upward pressure upon the trolley wire in excess of the tension in the spring 10, will cause the trolley wire to be raised. This action is found to be of considerable benefit, as it prevents what is termed, hard spots, in the trolley construction where the trolley wire is rigidly supported, and such hard spots tend to cause a rebound of the trolley wheel and consequent 30 arcing. If the trolley wire is permitted to rise and fall with the passage of the trolley wheel at the point of the support, the rebound of the wheel is either eliminated wholly or to a large degree with consequent 35 elimination of arcing.
- 35 It will be evident that having installed the device upon an overhead hanger, that the jaws are free to be rotated into alignment with the trolley wire, and having been positioned in alignment with the trolley wire, that rotation of the operating member 4 in the right direction will move the jaws into gripping engagement with the trolley wire.
- 40 45 50 55 60 65 In installing my improved clamp the end

of the member 1 is positioned against the end of the member S and the jaws and operating member are then pressed upwardly thereby compressing the spring 10 and then rotated until the lug 3 engages with the slot 9. (See Fig. 6.) Continued rotation of the jaws 13 will cause all parts to rotate in unison and the member 1 will be moved upwardly upon the stud S until it engages the lower face of the hanger H. The upward pressure upon the jaws 13 is then removed and the spring 10 will cause the members to return to their normal position, as shown in Fig. 5. The device is now installed upon the hanger H and the parts are free to rotate relative to the hanger. The jaws are now rotated into alignment with the trolley wire and if the jaws are not sufficiently open to receive the trolley wire, the operating member 4 is rotated in the proper direction thereby moving the jaws to a more open position. The trolley wire is then inserted between the lips 14 of the jaws, as shown in Fig. 5, and the operating member 4 is rotated in the proper direction to move the intermediate member 7 upwardly or toward the hanger, the jaws being prevented from rotation by the insertion of the trolley wire 15 therebetween. This will move the jaws into engagement with the trolley wire 15 and a further gripping action can be secured by applying a wrench to the faces 21 of the operating member 4. The relation of the parts when installed is shown in section in Fig. 3.

55 60 65 70 75 80 85 90 95 100 105 110 115 120 125 130

It will be evident that in order to remove the trolley wire from the clamp and the clamp from the hanger, that the operations just described should be reversed.

Modifications from the single preferred embodiment of my invention, as herein disclosed, will be evident to those skilled in the art and other objects and uses no doubt will disclose themselves to others, all of which will fall within the scope of my invention.

I claim:

1. A conductor clamp comprising a pair of jaws to grip the conductor, supporting means to secure the clamp to a hanger, means to move the jaws either into or out of engagement with the conductor and to permit the jaws to be rotated relative to the supporting means and yielding means permitting the jaws to be slidably moved towards the supporting member.
2. A conductor clamp comprising a pair of jaws to grip the conductor, supporting means to secure the clamp to a hanger, means to move the jaws either into or out of engagement with the conductor and to permit the jaws to have unlimited rotation relative to the supporting means, means permitting the jaws to be slidably moved towards the supporting means and means to limit said movement.

3. A conductor clamp comprising a pair of jaws to grip a conductor, supporting means to secure the clamp to a hanger, means connecting the support and jaws in 5 longitudinally slidable relation to permit the jaws to interlock with the supporting means in one longitudinal position and to be free of the supporting means in the other longitudinal position and means to move the 10 jaws into engagement with the conductor.
4. A conductor support comprising supporting means to secure the clamp to a hanger, a pair of jaws to grip a conductor, means connecting the jaws and support 15 means and permitting the jaws to slidably move toward and away from the supporting means for the purpose described, means limiting the movement of the jaws away from the supporting means and yielding 20 means to move the jaws away from the supporting means.
5. A conductor support comprising supporting means to secure the clamp to a hanger, a pair of jaws to grip a conductor, 25 means securing the jaws to the supporting means in slidable relation and adapted to move the jaws into engagement with the conductor when rotated and yielding means interposed between the supporting means 30 and the jaws to yieldingly hold the supporting means and the jaws apart.
6. A conductor support comprising supporting means to secure the clamp to a hanger, a pair of jaws to grip a conductor, 35 an intermediate member to support the jaws and an operating member to secure the intermediate member to the supporting means and permit the jaws to be slidably moved into or out of interlocked relation to the 40 support and to move the jaws into engagement with the conductor, when rotated.
7. A conductor clamp comprising a pair of jaws to grip a conductor, supporting means to secure the clamp to a hanger, 45 means connecting the jaws and support in longitudinally slidable relation to permit the jaws to interlock with the supporting means in one longitudinal position and to be free of the supporting means in the other 50 longitudinal position, means to move the jaws into engagement with the conductor and yielding means tending to move the jaws free of supporting means.
8. A conductor clamp comprising a sup- 55 porting means, a conductor gripping means mounted to rotate relative to the supporting means, means to move the gripping means into engagement with the conductor, intermediate means to interlock with the supporting 60 means at will to rotate the jaws simultaneously with the supporting means and means yieldingly holding the intermediate means and supporting means normally out of interlock.
9. A conductor clamp comprising a sup- 65 porting means, a conductor gripping means, means to move the gripping means into engagement with the conductor, intermediate means to interlock with the supporting means at will to rotate the jaws simultaneously with the supporting means and means yieldingly holding the intermediate means and supporting means normally out of interlock. 70
10. A conductor clamp comprising a sup- 75 port, a pair of jaws, a member to engage the jaws and the support in rotatable relation, intermediate means supported by the member and engaging the jaws and longitudinally movable relatively to the 80 member and the support and means on the member engaging means on the intermediate means to move the jaws when the member is rotated.
11. A conductor clamp comprising a sup- 85 porting means, a pair of relatively rotatable coacting members rotatably mounted on the supporting means and in slidable and unlimited rotation relation thereto, a pair of jaws secured to both members and movable into engagement with a conductor when the members are rotated relative to each other. 90
12. A conductor clamp comprising a sup- 95 porting means, a pair of coacting members each rotatable relative to each other and to the supporting means and mounted thereon, the said members movable longitudinally of each other, means yieldingly resisting the movement of the coacting members relative to the supporting means and a pair of jaws secured to each member and movable into engagement with a conductor when the members are moved in a 100 relative longitudinal direction. 105
13. A conductor clamp comprising a pair of jaws, a pair of members secured to each jaw and movable longitudinally of each other to move the jaws into engagement with a conductor and supporting means to 110 secure the parts to a hanger and having free and unlimited rotation relative to the jaws. 115
14. A conductor clamp comprising a pair of jaws, a pair of members secured to each jaw and movable longitudinally of each other to move the jaws into engagement with a conductor and supporting means to 120 secure the parts to a hanger and having free and unlimited rotation relative to the jaws while in one position relative to said members and interlocked with one of said members when in another relative position with respect to said members. 125
15. A conductor clamp comprising a pair of jaws, a pair of members secured to each jaw and movable longitudinally of each other to move the jaws into engagement with a conductor and supporting means to 130 secure the parts to a hanger and having

free and unlimited rotation relative to the jaws while in one position relative to said members and interlocked with one of said members when in another relative position 5 with respect to said members and yielding means normally holding the supporting means in the first said position.

16. A conductor clamp comprising a pair of jaws, a pair of members secured to each 10 jaw and movable longitudinally of each other to move the jaws at will, into or out of engagement with a conductor, supporting means to secure the parts to a hanger and to have two positions relative to the 15 jaws, one of limited rotation and the other of unlimited rotation, and slideable in a longitudinal direction relative to the jaws to one or the other of the positions.

17. A conductor clamp comprising supporting means, gripping means to engage a 20 conductor, means securing the supporting means and the gripping means together and movable into and out of the interlocked rotatable relation with the supporting means and to move the gripping means into 25 engagement with the conductor.

18. A conductor clamp comprising a pair of jaws, means to secure the jaws in pivotal

relation, operating means associated with the said means to move the jaws into engagement with the conductor, supporting means rotatably associated with the operating member for securing the clamp to a hanger and arranged to interlock at will with the first said means. 30

19. A conductor clamp comprising a pair of jaws, means to secure the jaws in pivotal relation, operating means associated with the said means to move the jaws into engagement with a conductor, supporting 40 means rotatably and telescopically associated with the operating member and means yieldingly holding the supporting means and operating member in a distended relation as and for the purpose described. 45

20. A conductor clamp comprising a pair of jaws, supporting means to secure the clamp to a hanger, means normally permitting rotation of the jaws relative to the supporting means, means permitting interlock at will of the jaws and supporting means and yielding means normally holding the said parts out of interlock. 50

In testimony whereof I affix my signature.

HOMER P. CHANDLER.
